PAPER CLIP BOARD

Frederick P. Robbins, Highland Park, Ill.

Application June 7, 1949, Serial No. 97,633

1 Claim. (Cl. 24—66)

1

The present invention relates to a clipping device and more particularly to a clip board or the like retainer for sheet material provided with a novel form of ball bearing clip.

The clipping device of the present invention is particularly adapted to maintain a plurality of sheet-like members in assembled relation, such as for retaining a plurality of sheets of paper in position upon a backing surface. The device includes a pair of cooperating clamping elements urged together into clamping relation by resilient spring means. More specifically, the clamping members are provided with registering recessed or apertured portions adjacent one end of each of the members, the recesses receiving a pivot member, such as a ball bearing, interposed between the members. Resilient means, such as resilient clamping springs, are provided to urge the clamping members together into clamping relation about the pivot members interposed therebetween.

Clipping devices generally similar to those above described have been known in the prior art, and various means have been proposed for opening the clamping members from clamping relation against the action of the resilient clamping spring. However, the prior art devices have suffered from various shortcomings, including relatively great overall length, clumsiness in use, and the necessity of exerting considerable force to open the clamping members from engagement.

The present invention now specifically remedies these faults of the prior art clipping devices by providing an improved opening means for such devices. In general, such opening means may suitably comprise a lever carried by one of the clamping elements for pivoted movement relative thereto and having an elongated lever arm for movement in contact with one of the clamping members to provide a mechanical advantage for easily opening the clamping elements. Actually, the opening of the clamping elements is accomplished by movement of the lever arm about the pivot member as a fulcrum against the action of the clamping spring, the mechanical advantage thus obtained aiding considerably in opening the device.

In one embodiment of the clipping device of the present invention, movement of the opening lever about its pivot point against the action of the clamping spring causes engagement between a shoulder formed on the opening lever and one of the clamping elements to lift or otherwise move the one clamping element from en-

2

gagement with that clamping element by which the lever is pivotally carried. In this embodiment of the invention, the opening lever is capable of sufficient pivoting movement to wedge a portion of the opening lever between the open clamping elements so that the resilient spring means urges the clamping members into wedged engagement with the opening lever shoulder to maintain the clamping elements in open position. Upon return pivoting movement of the opening lever, the clamping elements are again placed in clamping relation.

In the other embodiment of the present invention, the clamping lever is pivotally attached to one end of one of the clamping elements and is capable of pivoting movement relative to that clamping member, so that the opening lever is effectively an extension of the clamping member, and movement of the opening lever against the action of the resilient spring means causes opening of the clamping members from clamping relation.

Each of the two embodiments of the clipping device of the present invention are readily adapted to form a clip board or the like, one of the clamping members serving as a backing surface for sheet material and the other clamping members being urged into clamping relation with the sheet material thereon. Thus the clip board backing surface itself serves as one element of the clamping device.

It is, therefore, an important object of the present invention to provide an improved, easily employed, inexpensive form of clipping device equipped with opening means.

Another important object of the present invention is to provide an improved ball bearing clipping device, one of the clamping elements of the device serving as a backing member therefor with the bearing elements of the device being seated within complementary recesses formed in the backing member and in the other clamping element, one of the clamping elements also pivotally carrying an opening lever for urging the clamping elements from clamping engagement.

It is a further important object of the present invention to provide an improved ball bearing clipping device including a pair of cooperating clamping elements, means urging the elements into clamping relation, and means pivotally carried by one of the clamping elements for urging the elements from clamping relation against the action of the resilient spring.

Other and further important objects of this invention will be apparent from the disclosures

in the specification and the accompanying drawings.

On the drawings:

Figure 1 is a plan elevational view of a clipping device of the present device;

Figure 2 is a sectional view taken along the plane II-II of Figure 1;

Figure 3 is a sectional view similar to Figure 2 showing the clamping elements of the device in open position;

Figure 4 is a plan elevational view of a modified form of clipping device of the present invention;

Figure 5 is a sectional view taken along the plane V-V of Figure 4; and

Figure 6 is a view similar to Figure 5 showing the clamping elements in open position.

As shown on the drawings:

In Figure 1, reference numeral 10 refers generally to a clipping device of the present invention including a pair of cooperating clipping elements 11 and 12.

The element 11 may desirably take the form of a plane sheet of metal, plastic, wood or fibrous material capable of serving as a backing element of a clip board or the like. The clamping element 12 is formed of a similar suitable sheet material and is provided with a terminal downturned flange 13 at one end thereof, generally rectangular central slot 14, and a downturned flange 15 adjacent the other end thereof. The downturned flange 15 is provided with a terminal, outturned end portion 16.

A plurality of spaced bearing elements, preferably in the form of a ball bearing 17, are interposed between the clamping elements 11 and 12, the bearings 17 being maintained in position between the elements 11 and 12 by means of complementary recesses or dished portions 18 and 19 formed in the members 11 and 12 respectively. If desired, the recesses 18 and 19 may be provided by apertures extending through the members 11 and 12, respectively, and of a diameter considerably less than that of the ball bearings 17. The members 11 and 12 are urged into clamping relation by means of resilient springs 20, preferably in the form of slit, cylindrical, resilient sleeves engaging the members 11 and 12 inwardly of the recesses 18 and 19 respectively, and encircling the adjacent ends of the members 11 and 12 and the bearings 17.

An opening lever 21 is provided for urging the members 11 and 12 from their clamped position shown in Figures 1 and 2. The lever 21 includes an elongated, slightly arcuate lower portion 22 interposed between the members 11 and 12 and having oppositely directed, outwardly extending upper shoulders 23 for engaging the inner surfaces of the member 12. The clamping member 11 is provided with a plurality of spaced recesses 24 formed in the upper surface thereof for receiving depending projections 25 formed integrally with the lever 21. The lever arm 26 is provided centrally of the lever 21 to extend upwardly through the aperture 14 of the clamping member 12, the lever arm 26 being offset as at 27 to overlie the upper surface of the member 12.

The operation of the clipping device 10 and the opening of the clamping elements 11 and 12 will be understood from Figures 2 and 3 of the drawings. It will be seen that upon movement of the lever arm 26 from its position in contact with the upper surface of the arm of the clamping member 12, the shoulder 23 bearing against the under surface of the member 12 will cause

the member 12 to become elevated as seen in Figure 3. The movement of the opening lever 21 about its pivoting point in the recess 24 will be accomplished against the action of the spring 30 with the movement of the clamping members taking place about the ball bearing 17.

It will be seen from Figure 3 that the resilient action of the spring 20 when the clip is open will merely urge the members 11 and 12 into tighter wedging engagement with the shoulder 23 of the lever 21 and the clip cannot be closed by the action of the spring when in the open position of Figure 3. The clamping members 11 and 12 are thus maintained in open position so that sheet material 28 may be inserted therebetween the sheet material being clamped between the dependent flange 13 of the member 12 and the upper plane surface of the member 11 upon return movement of the lever to the position of Figure 2.

In the embodiment of the invention shown in Figure 4, reference numeral 30 refers generally to a modified form of clipping device including a pair of cooperating clamping elements 31 and 32 formed of suitable material as hereinbefore described in connection with the embodiment of Figures 1-3.

The clamping element 31 is similar in design and construction with the element 11 as hereinbefore described, the element 31 being provided with a recess 33 similar to the recess 18. The clamping member 32 is provided with a downturned flange 34 similar to the flange 15 of the element 12, the flange 34 terminating at a terminal portion 35 recessed as at 36. A ball bearing 37, similar to the bearing 17, is interposed between the members 31 and 32 in seated engagement with the recesses 33 and 36. A spring 38, similar to the spring 20, is provided to encircle the ball bearing 37 and the adjacent ends of the members 31 and 32.

That end of the clamping member 32 opposite the terminal portion 35 is secured to a cover member 39 of the same general configuration as the base member 31 and coextensive therewith. The hinge connection of the member 39 to the member 32 includes alternate deformed portions 40 and 41 formed integrally with the members 32 and 39 respectively. The deformed portions 40 and 41 encircle a hinge pin 42 passing centrally therethrough and coextensive with the width of the members 32 and 39. The member 39 when in the solid line position shown in Figure 5 overlies the sheet material 43 supported by the upper plane surface of the member 31 and thus serves as a cover which may be pivoted about the pivot pin 42 in the dotted position of Figure 5 so that the uppermost sheets 43 is accessible for writing, reading or other purposes.

In Figure 6, it will be seen that the cover member 39 is also capable of serving as an opening lever for moving the clamping members 31 and 32 from clamping engagement against the action of the spring 38. The cover member 39 may be pivoted about the pin 42 to lie against the clamping member 32 with further movement of the cover member 39 causing movement of the member 32 about the bearing 37 against the action of the spring 38 to remove the members 31 and 32 from clamping engagement.

It will, of course, be understood that various details of construction may be varied through a wide range without departing from the principles of this invention and it is, therefore, not the purpose to limit the patent granted hereon

otherwise than necessitated by the scope of the appended claim.

I claim as my invention:

A clipping device comprising a backing member having a first recess formed adjacent one end thereof and another recess adjacent thereto, a clamping element overlying said one end of said backing member and normally extending into contact therewith in spaced relation to said first recess, a bearing member interposed between said backing member and said clamping element and seated in said first recess, said clamping element having a slot therein overlying said second recess, resilient means enclosing said bearing means and acting on said backing member and said clamping element to urge the same into contact, and an elongated lever having one end pivotally seated in said second recess and an opposing end portion projecting through the slot formed in said clamping element into normal surface engagement with said clamping element, said lever having integral shoulders intermediate its length for slidably engaging portions

of said clamping element on the sides of said slot, said lever being pivotal with respect to said backing member and said clamping element toward a plane aligned with said second recess and normal to said backing member for retaining said clamping element in open position.

FREDERICK P. ROBBINS.
